UNITED STATES PATENT OFFICE.

ROBERT C. CHILD, OF BROOKLINE, MASSACHUSETTS, ASSIGNOR, BY MESNE ASSIGNMENTS, TO THE LAMSON COMPANY, OF BOSTON, MASSACHUSETTS, A CORPORATION OF MASSACHUSETTS.

SELECTOR DEVICE.

Application filed December 8, 1921. Serial No. 520,877.

To all whom it may concern:

Be it known that I, ROBERT C. CHILD, a citizen of the United States of America, and resident of Brookline, in the county of Norfolk and State of Massachusetts, have invented new and useful Improvements in Selector Devices, of which the following is a specification.

This invention relates to selector, assorting or separating devices adapted to separate moving articles or bodies into different classes; for example, devices for assorting carriers moving in pneumatic despatch tubes so that one class of carrier takes one path and another class takes another path. For instance, in pneumatic despatch tube systems, one class of carrier may be employed for cash transactions and a carrier of another class may be employed for credit transactions, and it may be desired to provide for delivering these classes of carriers to different destinations. There have been sundry prior proposals of devices for this general purpose, none of which is altogether satisfactory in respect to compactness, simplicity and durability, or the certainty of operation and low cost connected by these qualities.

Objects of the present invention are to provide an automatic separator device adapted certainly to deliver carriers of one class laterally of the path normally taken by them, and to permit carriers of the other class to pass unhindered toward their normal destination. Further objects of the invention are to provide a device of this class operating solely by the energy of the moving carrier; having as few moving parts as possible, and which may be installed simply and expeditiously at any part of a pneumatic tube; and which shall be certain in operation, simple, durable, and inexpensive.

The invention will now be described in connection with certain species only illustrating the genus of the invention. As shown in the accompanying drawings,—

Fig. 1 is a side elevation illustrating the idle or waiting-action position of the device and showing one class of carrier;

Fig. 2 is a similar view, illustrating the position of the parts when a carrier of the other class is passing;

Fig. 3 is a section on line 3—3 of Fig. 1;

Fig. 4 is a section on line 4—4 of Fig. 1;

Fig. 5 is a view similar to Fig. 1, but illustrating a modification;

Fig. 6 is a view similar to Fig. 2, illustrating another position of the device of Fig. 5; and

Fig. 7 is a section on the line 7—7 of Fig. 5.

When a despatch carrier is moving, either under an impressed velocity or driven by an air current, and is traveling in the axial direction of a tube such as shown at 1, interruption of the flight of the carrier by a projection or abutment encountering the carrier at one side of its center of gravity (or center of pressure, when driven) serves to convert the energy of translation into energy of rotation, resulting in a relatively strong tendency to rotate the carrier about the point of its contact with such projection or abutment, the trailing end of the carrier moving toward the opposite side of the tube from the position of the obstruction.

In accordance with the present invention this action is utilized to eject a carrier of one kind from the tube through a lateral opening provided in the tube, as shown at 2 for example, by causing carriers of this class to encounter a normally rigid or fixed but automatically removable abutment device 3, adapted normally to stand at one side of the path taken by the center of gravity (or pressure) of the carrier, for example, at one side of the tube and opposite the lateral opening 2. Whenever the abutment device 3 is positioned in the path of the carrier, any carrier, upon encountering the abutment, will be thrown laterally by its own momentum through the opening 2 in the direction of the arrow *a*, Fig. 1.

In the preferred construction, the abutment device 3 is sufficiently wide to constitute a seat defining a chord of the circular surface of the end of the carrier of substantial length. As best shown in Fig. 3, for instance, the abutment device 3 is formed as a lever comprising laterally spaced abutment elements providing the abutment surfaces 3^a, 3^b respectively. This lever preferably is made as a U-shaped casting or stamping having downwardly extending arms 3^c and 3^d, and having an integral web 3^e uniting these abutment elements and lying in a plane slightly below the surfaces 3^a and 3^b. The arms 3^c, 3^d are journaled at their lower ends to turn about an axis 5, defined by a pivot screw 6 mounted in lateral ears projecting from a frame or support presently

to be described. The axis 5 is near the periphery of the tube 1, while the abutment surfaces 3^a, 3^b which receive the shock of the carrier normally lie just within the tube 5 and substantially above such axis. As thus arranged, the center of figure of the lever lies between the vertical plane of its axis and the adjacent wall of the tube. The tendency of the lever to swing toward the tube 10 is limited by stop means 3^y, 27 presently described. Thus when subjected to the blow of a carrier, there is no component of the force of impact tending to swing the lever outwardly from the tube, the residual of 15 this force, on the contrary, tending to hold the abutment 3^a, 3^b in place, so that the abutment is rigid when operative, and its proper function is assured. By reason of the very short moment arm through which such force 20 acts, substantially the entire blow is transmitted lengthwise of the arms 3^c, 3^d to the strong pivot screw 6. The device is thus capable of withstanding repeated shocks 25 from heavy carriers without appreciable deterioration.

Since the carrier bottoms on the abutment at points lying in the respective surfaces 3^a, 3^b, the turning movement of the carrier in the direction of the arrow *a* will take place 30 accurately at right angles to the line defined by these points of contact with the carrier head. The direction in which the carriers are ejected from the opening 2 is thus relatively certain, being subject to slight variation 35 only, due to such eccentric displacement of the carrier in its tube as may occur, and the carriers thrown through the opening 2 may be received in another tube, a chute, basket, or other receptacle (not shown) and 40 with little danger of displacement or failure to deliver the carrier into such receptacle.

In the arrangement shown it is provided 45 that only such carriers as have hollow ends 9 shall be thrown through the aperture 2. Other carriers having solid ends 10 as shown in Fig. 2 are designed to pass on through the continuation 1^b of the tube 1. To accomplish this the abutment 3 is withdrawn laterally through an aperture 12 in the tube 50 1 before any part of a carrier having a solid end 10 can contact therewith. In the preferred construction shown, this is accomplished by the employment of a detector lever arranged to rotate about an axis 16 55 above and to the left of the axis 5, such lever comprising an operating member 17 terminating in a rounded contact point 18 which is normally disposed substantially centrally of the tube 1 and which stands somewhat above the normal plane of the abutment surfaces 3^a, 3^b.

In one form, the detector lever is of the angular or substantially V shape shown, comprising the pivoted portion 15 and the operating arm 17 above referred to, the

latter arm being of substantially arcuate shape having its center of curvature at the axis 16. The member 15 is also preferably of curved form as illustrated.

In order to actuate the abutment 3 the 70 detector lever carries a transverse pin 20 preferably arranged at a point much nearer the axis 5 than are the abutment surfaces 3^a, 3^b. In the form illustrated in Figs. 1 and 2 the detector lever is provided with a 75 notch 21 adjacent to the junction of the members 15 and 17 thereof and outward of the pin 20, such notch serving to receive the bridge member 3^c of the abutment at one extreme position of the latter, to limit the 80 motion of the lever abutment in one direction.

The parts are normally held in the position shown in Fig. 1 by suitable resilient means, such for example as two light 85 springs 25 hooked over pins in the arms 3^c, 3^d respectively, and secured at their other ends to lugs 26 projecting from an upper member 27 of a frame or support for the above described parts. Preferably this 90 frame or support comprises the upper and lower retaining members 27, 28 respectively, rigidly connected by an integral vertical strut such as 29 at each side of the tube. The lower member 28 of the frame or support 95 is provided at one side with the lugs 7 having aligned openings for the reception of the pivot screw 6, and is also furnished with the preferably integral binding members 30 having lugs 31 provided with openings for the clamping bolt 32 adapted to pinch the split ring made up of the parts 28 and 30 tightly about the tube 1. The upper member 27 of the frame or support 100 may terminate laterally in the inwardly 105 directed hook members 33 (Fig. 3) adapted to lap over the lateral margins of the tube 1 at the opening 2. Member 27 also carries the lugs 35, 36 in which is mounted a pin providing the axis 16 for the detector 110 lever 15.

The member 17 of the detector lever moves through an opening 13 in the tube 1. The abutment lever and detector lever may be provided respectively with any suitable 115 limit stops for determining their normal inner position. Preferably (as shown) such stops take the form of integral projections 3^y and 15^b, respectively engageable with the upper member 27 of the frame or support 120 and with the pivot screw 5.

In operation, assuming that a carrier having a solid head 10 is passing down the tube 1 (Fig. 2) its lower end 10 will encounter and swing the detector lever 18 downwardly 125 and outwardly about the axis 16, the pin 20 in turn driving the abutment 3 outwardly about the axis 5, the abutment surfaces 3^a, 3^b moving rapidly during the first part of the motion of the lever through the 130

wall of the tube, and out of the path of the carrier. Since this movement of these surfaces is substantially in the direction of their lengths, any possibility of engagement of the head of the carrier by them is avoided. The pin 20 engages the lever arms 3^c, 3^d at a point relatively near to the axis 5 to enable slight movement of the member 17 and its pin 20 to result in a relatively large movement of the abutment. The rounded detector end 18 of lever 15, 17, now moves down with the forward end of the carrier without substantially affecting the lateral position of the carrier until the end 18 leaves the tube through the lower opening 13. Further motion of the abutment and the detector lever is limited by engagement of the part 3^c in notch 21. The parts thus remain until passage of the carrier permits the springs 25 to restore them to the position of Figs. 1 and 3.

When, however, a carrier having a hollow end 9 passes down the tube, such hollow end permits contact of the carrier with the abutment without contact of the carrier with the end 18 of the detector lever, so that the abutment lever remains in its operative position and the carrier is thrown laterally from the tube as above described.

The same operations may be effected by the modified form of device shown in Figs. 5, 6 and 7, in which the detector lever 15^a is shown as a continuous arcuate shaped stamping or casting having the arm 17^a and the contact point 18^a, and provided with a transverse actuating pin 20^a. The abutment lever in this case may be a stamping 59 having an abutment surface at 60, and provided with a cam slot 61 for the reception of the pin 20^a. The abutment lever 59 may be and preferably is duplicated as shown, to straddle lever 15^a, and may turn on or with the pivot pin 6^a. When duplicated, the levers 59 are preferably keyed to the pivot pin. A single light spring 51 may be employed for restoring the parts to normal position, for instance being coiled about the pin 16^a forming the axis about which the detector lever swings, and having one end 52 engaging the edge of the lever 15^a and having its other end 53 engaging the lug 35^a of the upper member 27^a of the supporting frame. The operation of the device shown in Fig. 5 is substantially the same as that of the device illustrated in Fig. 1. Limitation of outward movement of the parts is by the pin 20^a and slot 61.

Other variations will be obvious to those skilled in the art. It should be noted that in either form of the device as illustrated there are but two necessary moving parts. These can be made with sufficient accuracy and of great rigidity and durability as castings, stampings or drop-forgings. The axes upon which the respective parts turn at 5

and 16 are fixedly related by the frame or support comprising the members 27, 28 and 29 so that ill-advised displacement by the workman is improbable.

To install a device of the type described, the openings 2, 12 and 13 may be made with a saw anywhere along a pipe line and the frame comprising the members 27, 28 and 29 together with the operating levers mounted thereon may be clamped in place. To facilitate such application of the frame, the binding members 30 are preferably made thin enough to be bent open to admit the full diameter of the tube whereupon they are closed together and the clamping bolt 32 may be inserted. Having adjusted the device, its position may be fixed if desired by soldering the vertical strut 29, or other part of the frame, to the tube 1.

I claim:

1. A selector device for assorting despatch carriers of different configurations moving in a given path, comprising a rigid abutment member normally projecting into contact with carriers moving in said path, and movable means actuatable upon the approach of a carrier of given configuration toward the abutment for removing said abutment from said path.

2. A selector device for despatch systems for diverting moving bodies from their normal path of travel comprising a normally fixed abutment member normally projecting into such path and engageable by a portion of a moving body at a point to one side of and in advance of the center of figure of such body whereby the center of figure thereof is caused to describe an arcuate path having such point of engagement as an axis.

3. A selector device for diverting pneumatic carriers from their normal course of travel comprising a rigid and unyielding member normally projecting into said path and constructed and arranged to engage a carrier moving along said path at a point to one side of the center of said carrier.

4. Pneumatic despatch mechanism having therein, in combination with carriers and a tube for directing them, a normally rigid abutment on one side of the path taken by the center of the moving carriers, and thereby adapted to induce a carrier striking it to be thrown laterally of said path, and means for preventing contact with the abutment of a carrier of a particular kind.

5. Pneumatic despatch mechanism having therein, in combination with carriers and a tube for directing them, a normally rigid abutment on one side of the path taken by the center of the moving carriers, and means for removing the abutment from the path of a carrier of a particular kind.

6. Pneumatic despatch mechanism having therein, in combination with carriers and a tube for directing them, a normally rigid

abutment on one side of the path taken by the center of the moving carriers, and means actuated by a carrier of a particular kind for removing the abutment from the path of a carrier of that kind.

7. In combination with a pneumatic tube, selecting mechanism for assorting carriers moving along said tube comprising a normally rigid abutment placed to arrest the normal forward movement of carriers of one configuration and thereby to convert the energy of translation of the carrier into energy of rotation with consequent bodily motion of the carrier laterally of the tube.

10 8. In combination with a pneumatic tube having a lateral discharge opening, selecting mechanism for assorting carriers moving along said tube in accordance with their respective configurations, said mechanism comprising a normally rigid abutment placed to arrest the normal forward movement of carriers of one configuration and thereby directly to convert the energy of translation of the carrier into energy of rotation with consequent bodily ejection of the carrier laterally from the tube through such discharge opening.

15 9. A selector device for assorting bodies of different configuration moving successively in a predetermined path comprising a device for obstructing the free passage of bodies of one configuration whereby to cause their lateral diversion from said path, and means including a detector device engageable by an approaching body of another configuration and actuatable thereby for positively moving said obstructing device from said path.

20 10. An assorting device for bodies moving in a predetermined path comprising a movable abutment member normally projecting into said path from and at one side of the center thereof, and so constructed and arranged as to tend to move further across said path under impact of a body thereon, a stop to prevent motion of the abutment under impact, and means whereby said abutment may be moved out of such path.

25 11. An assorting device for bodies moving in a predetermined path comprising a movable abutment member normally projecting into said path from and at one side of the center thereof, and so constructed and arranged as to tend to move further across said path under impact of a body thereon, a stop to prevent motion of the abutment under impact, and means adapted to be operated by a body of a certain configuration for positively moving the abutment out of said path prior to the passage of said body.

30 12. A selector device for changing the direction of moving bodies comprising an abutment lever on a pivot near one of its ends and at one side of the path of motion of said bodies and having an abutment sur-

face at its opposite end, said surface lying crosswise of the length of said lever and normally in said path, and between the pivot and an approaching body, whereby the abutment lever normally receives the impact of collision with the body in the direction of its length, and is removable about its pivot radially in respect to the path taken by the center of said body.

35 13. A selector device for assorting bodies moving in a predetermined path comprising an abutment on a pivoted lever normally extending in a direction substantially parallel to the path of movement of said bodies, the said abutment projecting transversely into said path for contact with bodies moving therein, and a stop for preventing turning motion of the lever on its pivot under the force due to impact of one of the bodies striking the abutment and acting in the direction of the length of the lever.

40 14. A device for assorting pneumatic carriers normally traveling in one direction in a tube, comprising a lever pivotally mounted outside said tube and at a point closely adjacent thereto, said lever extending from its pivotal point longitudinally of the outer surface of the tube in a direction opposite to the motion of the carrier, and an abutment element carried by the lever adjacent to its free extremity and extending laterally into said tube through an opening therein.

45 15. A mechanism for assorting carriers moving in a pneumatic tube comprising an elongate abutment member projecting into said tube through a lateral opening therein, and lying substantially in the direction from which the carriers approach, and supporting means for said abutment member, whereby upon impact of a carrier against said member substantially the entire force of the impact is transmitted along the abutment member to its supporting means.

50 16. Carrier separating devices for carrier despatch systems comprising a normally fixed movable member having thereon a carrier-diverting abutment, a detector lever having a part in the path of the carriers, means supporting the abutment member and the detector lever for relative movement, and means connecting the abutment member and said lever, whereby motion of one moves the other.

55 17. Carrier separating devices for carrier despatch systems comprising a normally-fixed movable member having thereon a carrier-diverting abutment, a detector lever having a part in the path of the carriers, means supporting the abutment member and the detector lever for relative movement, and means connecting the abutment member and said lever, whereby motion of one moves the other; in combination with carriers some of which are adapted to engage the detector lever prior to reaching the

abutment, and some of which are adapted to engage and be diverted by the abutment before moving the detector lever.

18. Carrier separating devices for carrier despatch systems comprising carriers, a carrier-diverting abutment lever normally held in the path of the carriers; a detector lever; a frame on which the detector lever and the abutment lever are pivoted respectively in such relation that a carrier encountering the detector lever will drive said detector lever from the path of the carriers, and a carrier encountering the abutment lever will hold said abutment lever rigidly in its normal position; in combination with means connecting said levers for motion together away from the path of the carriers.

19. Carrier separating devices for carrier despatch systems comprising carriers, a carrier-diverting abutment lever normally held in the path of the carriers; a detector lever; a frame on which the detector lever and the abutment lever are pivoted respectively in such relation that a carrier encountering the detector lever will drive said detector lever from the path of the carriers, and a carrier encountering the abutment lever will hold said abutment lever rigidly in its normal position; in combination with means connecting said levers for motion together away from the path of the carriers, means for limiting the motion of said levers, and means for returning them to their normal position after actuation.

20. A mechanism of the class described comprising an abutment member, a detector member, and means for pivotally supporting said members to swing about spaced axes and in opposite directions, and means whereby motion of a detector member causes motion of the abutment member to an operative position.

21. Separator mechanism comprising a movable abutment member, a detector member movable in a different path, and means whereby movement of the detector member is positively transmitted to the abutment member.

22. Separator mechanism comprising a pivoted abutment member, a pivoted detector member, and connections between said members whereby rotation of the detector member moves the abutment member positively and in an opposite rotative sense.

23. Separator mechanism comprising a movable abutment member, a movable detector element, and connections between said member and element constructed and arranged to cause movement of the detector element to produce movement of the abut-

ment member of a relatively greater amplitude.

24. Mechanism of the class described comprising a movable abutment member, and a detector lever pivotally supported adjacent to one of its extremities and having a detecting element at its other extremity, and means on said detector lever between its extremities for engagement with an element of the abutment member for imparting movement to the latter.

25. In a carrier assorting mechanism for pneumatic tubes a movable abutment member, a movable detector member, a surface on one of said members, and a pin on the other of said members contacting with said surface, whereby motion of the detector member is imparted to the abutment member.

26. In combination with a tube section forming a portion of the guiding means for pneumatic carriers, said tube section having a lateral opening therein, means for laterally deflecting the carriers comprising an abutment device normally rigidly held within the tube to be struck by carriers opposite said opening, said abutment being constructed and arranged to define an axis about which a carrier may turn in passing outwardly from the tube through said opening.

27. In combination with a pneumatic tube having an opening in its side, an abutment device normally rigidly held within said tube at a point substantially opposite said opening, said device comprising spaced surfaces affording points of contact for an approaching carrier which points define a chord of the circular end of the carrier of substantial length.

28. In combination with a pneumatic tube, a pair of axially spaced retaining members engaging the tube, a longitudinally extending strut rigidly uniting the retaining members, and carrier selecting means comprising a detector supported by one of said retaining members and an abutment supported by the other retaining member.

29. In combination with a pneumatic tube having an opening in its side, a frame comprising a retaining member provided with inwardly directed hooks at its ends, said hooks being constructed and arranged to engage the edges of the opening in the tube, and a carrier detector member pivotally connected to the retaining member.

Signed by me at Boston, Massachusetts, this sixth day of December, 1921.

ROBERT C. CHILD.
